UNITED STATES PATENT OFFICE

ALFRED G. SLATCHER, OF CLEVELAND, OHIO, ASSIGNOR TO THE CLEVELAND ROCK DRILL COMPANY, OF CLEVELAND, OHIO

ROCK DRILL OF THE VALVELESS TYPE

Application filed February 25, 1928. Serial No. 257,084.

The present invention is directed to improvements in rock drills of the valveless type.

The primary object of the invention is to provide a device of this character so constructed that the piston hammer during its movement controls the admittance of the motive fluid to and from the hammer without the use of complicated valve mechanisms.

10 Another object of the invention is to simplify the construction of drills of this type, the construction being such that the piston hammer will be rapid and positive in its operation.

15 Another object of the invention is to provide a drill of this kind so constructed that it can be manufactured at a relatively small cost, and one which is durable and efficient in operation.

20 With these and other objects in view, this invention resides in the novel features of construction, formation, combination and arrangement of parts to be hereinafter more fully described, claimed and illustrated in the accompanying drawings, in which:

Figure 1 is a longitudinal sectional view. Figure 2 is a sectional view taken transversely through the exhaust port.

Referring to the drawings, 1 designates the 30 cylinder having front and rear piston chambers 2 and 3, respectively, the diameter of the former being greater than the latter to accommodate the differential piston hammer 4. The rear piston chamber is formed in the cylinder block 5 and sleeve 6 which fits between the back head 7 and said block, said sleeve defining an annular chamber 8 between the back head and block. The block has a passage 9 formed longitudinally therein which affords communication between the relatively large constant pressure chamber 10 formed between the chambers 2 and 3.

The forward end of the chamber 2 is closed 45 by the tappet case 11, which as usual, is interposed between the front head 12 and cylinder 1, there being a tappet 13 shown in the case for striking the drill steel 14.

The chambers 2 and 3 are connected by a motive fluid passage 15 which has its ends

opening into the forward ends of the respective chambers.

The chamber 2 is open to atmosphere through the exhaust port 16. The piston hammer 4 is formed with a head 17 for movement in the chamber 2 and chamber 10, and further includes a stem 18 movable in the chamber 3 and sleeve 6, said stem having a reduced neck 18'. The head 17 is provided with an annular exterior groove 19 in which open the outer ends of the radially disposed ports 20, said ports having their inner ends opening into the forward end of the longitudinal bore 21 in the piston hammer, the rear end of said bore opening into the chamber 3, 65 while the forward end thereof stops at a point slightly beyond the inner ends of the ports 20.

The back head has carried thereby a spring controlled live air controlling valve 22 mounted in a chamber 23, the chamber being in communication with the chamber 8 through a port 24. The valve 22 is opened upon actuating the lever 25 pivotally mounted on the handle 26 carried by the back head, as is 75 customary.

As shown in Figure 1, the piston hammer is in position to begin its rearward stroke. Pressure fluid passes from the chamber 8, through passage 9 and into the pressure chamber 10, the pressure remaining constant as long as the valve 22 is open. As the piston hammer moves rearwardly the groove 18' is so located as to permit pressure fluid to pass through the passage 15 to act upon the 80 front face of the piston hammer, thus driving the same rearwardly to its fullest extent. When in this position, and just before the piston hammer starts on its forward stroke the ports 20 open into the chamber 10. It 85 will be of course understood that just before the piston hammer starts on its rearward stroke that the fluid will exhaust through the ports 20 to atmosphere through the exhaust port 16. Upon the completion of the rearward stroke the groove 19 is positioned in the chamber 10 so that pressure fluid from said chamber will enter the ports 20 and bore 21, thus acting upon the rear end of the piston to drive the same forwardly with- 100

out resistance since there is no pressure upon the front face of the piston due to the presence of the exhaust port 16.

What is claimed is:—

- 5 1. In a tool of the class described, the combination with a cylinder having large and small chambers, and a relatively large constant pressure air chamber therebetween, said cylinder having an exhaust port opening into
10 the large chamber, a piston hammer including a head and stem movable, respectively, in the large and small chambers, a reduced neck formed on the stem, said cylinder having a motive fluid conducting passage connecting the forward ends of the respective chambers, said stem and neck serving to alternately cut off and permit passage of motive fluid through the passageway to the large chamber, means controlled by the stem for
15 conducting motive fluid from the constant air chamber to the rear end of the stem, said head being subjected constantly to the pressure of the air in the constant air chamber.
20 2. In a tool of the class described, the combination with a cylinder having large and small chambers, of a piston hammer movable in the cylinder and including a head and stem movable, respectively, in the large and small chambers, said cylinder having a constant air chamber between the large and small chambers, a motive fluid passageway connecting the front ends of the respective chambers, a reduced neck formed in the stem, said stem and head having a bore formed therein for
25 conducting motive fluid from the constant air chamber to the rear end of the small chamber when the piston hammer is in one position, said neck permitting motive fluid from the constant air chamber to pass to the front end of the large chamber for action against
30 said head, when in another position, and means for exhausting fluid from the bore.
35 3. In a tool of the class described, a cylinder having large and small chambers, a relatively large constant air pressure chamber therebetween, a piston hammer including a head and stem movable, respectively, in the said chambers, said cylinder having a motive fluid conducting passage connecting the
40 front ends of the respective chambers, said piston hammer having a bore therein, and ports at one end opening into the pressure chamber intermittently to permit pressure fluid to pass to the rear end of the hammer
45 to act upon the stem, the cylinder having an exhaust port leading from the large chamber, the ports of the hammer discharging through the exhaust port when moved from the pressure chamber, and means carried by
50 the stem for controlling the flow of pressure fluid through the passage to the front end of the large chamber.
55 4. In a tool of the class described, a cylinder having a pair of chambers therein, a relatively large constant air pressure chamber

communicating with said chambers, a piston hammer including a head and a stem movable respectively in said chambers, there being a fluid conducting passage in said cylinder communicating with the front ends of said chambers, said piston hammer having an axial bore therein adapted to intermittently communicate with said pressure chamber to permit fluid to pass to the rear end of the hammer to act on the stem, there being an exhaust port communicating with the atmosphere from the forward chamber, said bore in the hammer intermittently communicating with said exhaust port when moved out of communication with the pressure chamber, and means carried by said stem for controlling the flow of pressure fluid to the front end of the forward chamber through said passage.

In testimony whereof I affix my signature. 85
